UNITED STATES PATENT OFFICE.

ALBERT O. GLASOW AND EDWARD L. ACKER, OF SAN PEDRO, CALIFORNIA.

COMBINED TOOTH-PASTE SQUEEZER AND BRUSH-HOLDER.

1,212,138.

Specification of Letters Patent. Patented Jan. 9, 1917.

Application filed August 2, 1915. Serial No. 43,279.

To all whom it may concern:

Be it known that we, ALBERT O. GLASOW and EDWARD L. ACKER, both citizens of the United States, residing at San Pedro, in the county of Los Angeles and State of California, have invented new and useful Improvements in Combined Tooth-Paste Squeezers and Brush-Holders, of which the following is a specification.

10 This invention relates to a combined tooth paste squeezer and brush holder, and pertains especially to a tube holder provided with means for discharging dentifrice from a tube.

15 It is an object of this invention to provide a toilet appliance for holding tooth brushes, a dentifrice container, and for feeding the dentifrice to a brush.

It is another object of this invention to 20 provide a dentifrice tube container holder equipped with a squeezer adapted to force dentifrice from a collapsible dentifrice tube, and to provide the said squeezer with means making it adjustable with respect to the 25 tube.

An embodiment of our invention is illustrated in the accompanying drawing, in which:

Figure 1 is a front elevation of the holder. 30 Fig. 2 is a side elevation showing a dentifrice tube in position, a brush upon the brush rest and the brush supported in the holder. Fig. 3 is a fragmentary section as seen on the line 3—3 of Fig. 1.

35 In the drawing, 4 indicates the holder, 5 the squeezer mounted upon the holder, 6 the bracket for supporting the brushes, and 7 the brush rest bracket.

The holder comprises an upright 8 formed 40 preferably of sheet metal having an off-set portion 9 adapted to be disposed against a wall and provided with an aperture 10 for the reception of a screw, nail or other convenient fastening means. At the lower 45 end of the off-set portion is the forwardly extending brush rest bracket 7 having up-standing flanges 8 and 9 so that the brush may be readily positioned to receive the tooth-paste. The upper portion of the up-right 8 is off-set as indicated at 11, and provided with an aperture 12 for the reception of a screw or nail to secure the holder to the wall. Arms 13 and 14 extend outwardly and are provided with pairs of ears 15 and 55 16, and 17 and 18 for gripping the handles

of brushes. Ears 15 and 18 may be conveniently formed by turning the ends of the arms forwardly. Ears 16 and 17 may be formed by slitting the arms and turning the lip formed forwardly. To provide means for supporting the weight of the tube and positioning it above the brush rest a supporting bracket 19 is conveniently formed by slitting the middle of the holder and turning the lip formed outwardly. The supporting bracket 19 is formed with an aperture through which the neck of the tube may extend.

The squeezer is comprised of a guide 20 having a bar 21 positioned to extend along the rear of the upright 8, and forwardly extending bearings 22 and 23 upon which is pivotally mounted the squeezer arm. Squeezer arm 24 is of bell crank form having a portion 25 extending to one side of the 75 pivotal axis rounded and adapted to engage the dentifrice tube. A finger portion 26 is provided which extends outwardly and may be conveniently engaged by the finger.

A collapsible dentifrice tube 27 is positioned upon the holder with the neck extending through the aperture in the supporting bracket 19. The closed end is positioned beneath the squeezer arm 25. The brushes are placed with the handles between the ears 85 15—16 and 17—18. In using the appliance a brush is removed from the brush holding ears and disposed with its back upon the brush rest 7 as indicated at 28. To discharge the dentifrice the finger end of the 90 squeezer 26 is pressed downwardly, thereby squeezing the tube and forcing paste from the end, the paste dropping upon the brush. The paste only continues to discharge during the time pressure is applied to the 95 squeezer.

It will be noted that we have provided a device which may be conveniently made of sheet metal. The holder proper is made from one piece of metal. The appliance may 100 be conveniently installed on a wall and provides all the means for holding the brush and dentifrice when the latter are not being used and also a convenient and sanitary means for feeding the dentifrice preparatory 105 to cleaning the teeth.

What we claim is:

A dental toilet appliance, comprising a standard having a laterally extending bracket portion for engaging a collapsible 110

dentifrice tube adjacent its outlet and maintaining said tube parallel and contiguous to said standard, a squeezer guide member slidably mounted on said standard, and a 5 two-armed squeezer pivotally mounted on said squeezer guide member on an axis in a plane parallel to the plane of said standard, one arm of said squeezer adapted to

rock toward said standard, the other arm forming a finger hold.

In witness that we claim the foregoing we have hereunto subscribed our names this 15th day of July, 1915.

ALBERT O. GLASOW.
EDW. L. ACKER.
